UNITED STATES PATENT OFFICE.

EDWARD A. MELLINGER, OF CHICAGO, ILLINOIS.

TELEPHONE SIGNALING SYSTEM.

1,140,329.

Specification of Letters Patent. Patented May 18, 1915.

Application filed May 9, 1913. Serial No. 766,558.

To all whom it may concern:

Be it known that I, EDWARD A. MELLINGER, a citizen of the United States of America, and resident of Chicago, in the county of Cook and State of Illinois, have invented a certain new and useful Improvement in Telephone Signaling Systems, of which the following is a specification.

My invention relates to improvements in telephone systems, and more particularly to the provision of means whereby a called subscriber may indicate to an operator the fact that a connection has been made with his line, which connection he desires to have released.

In automatic and semi-automatic telephone systems difficulty is often experienced owing to the fact that when a connection is set up between a calling and a called subscriber, which connection can only be released by the calling subscriber, the called subscriber's telephone is rendered inoperative for making a call as long as this connection is maintained. Thus a calling subscriber can either negligently or maliciously tie up another subscriber's telephone by failing to hang up his receiver so as to release the connection which he has established with the other subscriber.

It is the object of my invention to provide means whereby the subscriber whose telephone is thus tied up can signal an attendant at the exchange, who can then release the connection from his line.

My invention is especially useful in connection with automatic or semi-automatic telephone systems, but in certain broader respects it is likewise of value in connection with manual systems.

For the purpose of more particularly describing my invention I have illustrated the same in connection with an automatic connector switch which is adapted to automatically connect with a subscriber's line.

In the accompanying drawing I have represented diagrammatically an automatic connector switch F connected with an automatic subscriber's station A to which is allotted a line switch C. This connector F is of the type disclosed in United States Letters Patent No. 815,176, granted March 13, 1906, to Keith, Erickson and Erickson, but is slightly modified in order to adapt it for use in a two-wire system. Among other details it comprises a line relay 60, vertical and rotary magnets 61 and 62, pri-

vate magnet 103, release relay 63, release magnet 64, back-bridge relay 65, ringing relay 66 and a ringing cut-off relay 67.

The line switch C is of the general type disclosed in British patent to R. W. James No. 26,301 of 1906 and in the *Western Electrician* of Chicago, Illinois, of January 25, 1908, being, however, of the particular form shown in British patent to T. G. Martin No. 1419 of 1910. It will, of course, be understood that a master switch is employed with each group of these line switches, but as this feature is well known and is described in the patents referred to, and as the same forms no part of my present invention, it is not thought necessary to describe or illustrate the same.

The substation A is the well-known type, consisting of a receiver 2, transmitter 3, contact springs 9, 10 and 11, ringer 12, condenser 13 and an impulse transmitter or calling device represented by the impulse springs 4 and impulse wheel 5. Said calling device can, of course, be of any desired type, but I have represented diagrammatically one similar to that described in British patent to S. G. S. Dicker No. 29,654, of 1910.

Connection is made with the connector switch F over the trunk conductors 99 and 99^a, which connection can be established in any well-known manner, such as by automatic switches or by the aid of a manual operator's switchboard.

It will be seen that the connector switch F is provided with the ringing relay 66 by which ringing current is automatically applied to the called line. The ringing cut-off relay 67 is likewise provided, which operates in the well-known manner to prevent ringing current being applied to the line after the called subscriber has answered. Associated with this relay 67 there is a pair of additional contact springs 151, one of which is connected to a relay 150 which is preferably made slow acting, the other terminal of which relay is connected to the battery B. This relay controls through the medium of the springs 172 a local circuit containing an audible signal 170 in the form of a bell and a visual signal 171 in the form of a lamp. The other contact spring 151 is connected to a spring 152 of the back-bridge relay 65. This spring 152 is normally in engagement with the spring 199 which is connected to the wiper 106, which wiper,

when connection is made with a subscriber's line, is connected to battery. This arrangement is such that the circuit of the relay 150 can only be completed after a connection has been made with a subscriber's line and the relay 67 energized and the relay 65 de-energized.

In order to make my invention more clearly understood, I will now describe the 10 operation of the connector F and the signaling device H when connection is established with a called line. After a calling subscriber has extended his connection to the trunk conductors 99 and 99^a, which extend 15 to the connector F, impulses are then transmitted over these trunk conductors in the well-known manner in order to first operate this connector in a vertical direction, and then a second series of impulses are transmitted 20 over these conductors in order to rotate the switch on to the particular contact of the called subscriber's line. In a two-wire system of the character I have illustrated the circuit for the line relay 60 25 of the connector switch is closed when connection is established with the trunk conductors 99 and 99^a. The first series of impulses operates to de-energize this relay a varying number of times, depending upon 30 the number of impulses, the de-energizing of this line relay closing the circuit of the vertical magnet 61, which operates to raise the shaft in the usual manner. After the last impulse of the series is delivered, the 35 slow acting private relay 102, which is energized in series with the vertical magnet, de-energizes, thereby breaking the circuit of the private magnet 103 to allow the side switch to be released from the first to 40 the second position, transferring battery connection from the vertical magnet 61 to the rotary magnet 62. The next series of impulses is then transmitted over the trunk conductors and these operate to de-energize 45 the line relay 60 in the same manner above described, but the de-energizing of the line relay now operates the rotary magnet to rotate the shaft wipers 104, 105 and 106 on to the contact of the called subscriber's 50 line. After the last impulse of this series has been delivered, the private magnet again de-energizes and the side switch passes to the third position. Upon the side switch wiper 48 reaching the third position a circuit 55 is closed from ground G^e through said side switch wiper 48, private wiper 106 and through the hold-down coil 110 to the battery lead 100. The coil 110 energizes to attract the armature 111 to force the springs 112 together. Thus the connection is completed through the side switch wipers 46 and 47 and through the springs 112 to the substation A. The connection with ground G^e also provides a guarding potential 60 for the private contacts in the banks

of the connectors through which the called subscriber may be reached to prevent any other subscriber obtaining connection with said line while it is busy. Upon the side switch wiper 49 reaching third position battery current is supplied to the ringer relay 66, the circuit extending from ground G^e through the ringing interrupter 114, through relay 66, springs 113 and said side switch wiper 49 to the battery lead 100. 70 The relay 66, upon energizing, disconnects the calling line from the called line and connects the ringing current generator 116 with the called line to signal the called subscriber. The circuit of the relay 66 is interrupted intermittently by the interrupter 114 so as not to ring the subscriber continuously.

Upon the subscriber at the substation A answering the call the telephone is bridged 85 across the line and immediately, or as soon thereafter as the ringer relay 66 is de-energized, the back-bridge relay 65 is energized to reverse battery to the calling subscriber's line in the well-known manner. By the 90 same operation the ringing cut-off relay 67 is energized over a circuit extending from ground G^e through the side switch wiper 48, conductor 202, spring 199 and its front contact and through the relay 67 to the battery lead 100. The relay 67, upon energizing, breaks the circuit of the ringing relay at the springs 113 and closes a locking circuit for itself, which circuit extends from ground G^e through the side switch wiper 48, 95 springs 200 and relay 67 to the battery lead 100.

The connector switch is released over the calling end of the connection by opening the circuit which was closed over the trunk conductors 99 and 99^a during conversation, whereby the contact between the springs 10 and 11 is permanently broken, which causes the line relay 60 of the connector F to de-energize. Upon the relay 60 de-energizing, the holding circuit of the release relay 63 of the connector F is destroyed. The relay 63, upon de-energizing, completes the circuit of the release magnet 64 and so the connector is returned to its normal position. 110 Upon the shaft of the connector switch reaching its lowest position the circuit of the release magnet is opened at the spring 121.

Having now described the operation of the connector switch, I will describe the operation of the signaling device H by which an indication is given when a subscriber blocks or ties up some other subscriber's line. Upon the called subscriber hanging up his receiver while the calling subscriber has his receiver off the hook, the back-bridge relay 65 de-energizes, while the ringing cut-off relay 67 is still energized from ground G^e through the side switch wiper 48, springs 200 and through said relay to the battery 125 130

lead 100. When the relay 65 deenergizes, a circuit is closed from ground G⁶ through the side switch wiper 48, conductor 202, through the contact of springs 199 and 152, 5 conductor 203, through the contact of springs 151 and the winding of the solenoid or plunger relay 150 to the battery lead 100. The relay 150 thereupon energizes to attract its armature (which is arranged to 10 operate slowly), closing the circuit of the common alarm 170 in series with the lamp 171, which latter shows the location of the trouble indicated by the ringing of the bell 170. The plunger relay is arranged to operate slowly so as to give the calling subscriber a sufficient length of time in which 15 to hang up his receiver, if he intends to do so, before the springs 172 make contact.

It will thus be seen that I have provided 20 a very simple and efficient means whereby any called subscriber is enabled to signal an exchange attendant in case the calling subscriber either wantonly or negligently fails to release the connection within a reasonable time after the called subscriber has 25 hung up his receiver. The exchange attendant will therefore ascertain which switch has made connection with the line which is thus blocked and release it, thereby 30 by restoring said line to its normal operative condition.

While I have illustrated and described my invention in connection with a connector switch of a particular type, it will, of course, 35 be understood that my invention is not limited to such use, but is of much broader scope and is of value in connection with switches of other types used in automatic or semi-automatic systems, and is also useful 40 in connection with manual systems.

What I claim as my invention is:—

1. In a telephone system, a subscriber's 45 line, automatically progressively movable means for establishing connection with said line, a signal, means for preventing the display of the signal when connection is first made with said line, and means for displaying said signal upon the subscriber replacing his receiver upon the switch hook after said connection has been established.

2. In a telephone system, a subscriber's 50 line, means for establishing a connection with said line, a signal, and slow acting means for operating said signal after the subscriber on said line replaces his receiver upon the switch hook after said connection has been established.

3. In a telephone system, a subscriber's 55 line, an automatic connector switch for establishing connection with said line, a signal, and slow acting means for operating said signal after said subscriber has replaced his receiver upon the switch hook after the establishment of said connection.

4. In a telephone system, a subscriber's 60

line, a connector switch for establishing connection with said line, a relay in said connector, means for energizing said relay upon the response of the subscriber after connection has been established with the line, 70 means for maintaining said relay in an energized position until said switch is released, a second relay, means for energizing said second relay upon the response of the subscriber, means for deenergizing said second 75 relay when said subscriber replaces his receiver upon the hook, a signaling relay, and a circuit for said signaling relay controlled by said first two relays.

5. In a telephone system, a subscriber's 80 line, a connector switch for establishing connection with said line, a relay in said connector, means for energizing said relay upon the response of the subscriber after connection has been established with the line, 85 means for maintaining said relay in an energized position until said switch is released, a second relay, means for energizing said second 90 relay upon the response of the subscriber, means for deenergizing said second relay when said subscriber replaces his receiver upon the hook, a signaling relay, and a circuit for said signaling relay including normally open contacts of said first relay and normally closed contacts of said second 95 relay.

6. In a telephone system, a subscriber's 100 line, a connector switch for establishing connection with said line, a relay in said connector, means for energizing said relay upon the response of the subscriber after connection has been established with the line, means for maintaining said relay in an energized position until said switch is released, a 105 second relay, means for energizing said second relay upon the response of the subscriber, means for deenergizing said second relay when said subscriber replaces his receiver upon the hook, a signaling relay, and a circuit for said signaling relay adapted to be closed only after a connection has been established with said line and said first relay energized and said second relay deenergized.

7. In a telephone system, a subscriber's 110 line, a connector switch for establishing connection with said line, a relay in said connector, means for energizing said relay upon the response of the subscriber after connection has been established with the line, 115 means for maintaining said relay in an energized position until said switch is released, a second relay, means for energizing said second 120 relay upon the response of the subscriber, means for deenergizing said second relay when said subscriber replaces his receiver upon the hook, a slow acting signaling relay, and a circuit for said signaling relay controlled by said first two relays.

8. In a telephone system, a subscriber's 125 line, a connector switch for establishing con-

nection with said line, a relay in said connector, means for energizing said relay upon the response of the subscriber after connection has been established with the line, 5 means for maintaining said relay in an energized position until said switch is released, a second relay, means for energizing said second relay upon the response of the subscriber, means for deenergizing said second 10 relay when said subscriber replaces his receiver upon the hook, a slow acting signaling relay, and a circuit for said signaling relay including normally open contacts of said first relay and normally closed contacts of 15 said second relay.

9. In a telephone system, a subscriber's line, a connector switch for establishing connection with said line, a relay in said connector, means for energizing said relay upon 20 the response of the subscriber after connection has been established with the line, means for maintaining said relay in an energized position until said switch is released, a second relay, means for energizing said 25 second relay upon the response of the subscriber, means for deenergizing said second relay when said subscriber replaces his receiver upon the hook, a slow acting signaling relay, and a circuit for said signaling relay adapted to be closed only after a connection has been established with said line and said first relay energized and said second relay deenergized.

10. In a telephone system, a subscriber's 35 line, means for establishing a connection with said line, a pair of relays, means for energizing said relays upon the response of the subscriber after said connection has been established, means for deenergizing one of 40 said relays when the subscriber replaces his receiver upon the hook, a signal, and means

controlled by said relays for operating said signal upon the subscriber replacing his receiver upon the hook.

11. In a telephone system, a subscriber's 45 line, an automatic connector switch for establishing connection with said line, means for automatically supplying ringing current to said line, a ringing cut-off relay adapted to be energized upon the response of the subscriber, means for locking said relay in energized position, a back-bridge relay adapted to be energized upon the response of the subscriber, means for deenergizing said relay upon the subscriber replacing his receiver upon the hook, and a signaling relay including normally open contacts of said cut-off relay and normally closed contacts of 55 said back-bridge relay.

12. In a telephone system, a subscriber's 60 line, an automatic connector switch for establishing connection with said line, means for automatically supplying ringing current to said line, a ringing cut-off relay adapted to be energized upon the response of 65 the subscriber, means for locking said relay in energized position, a back-bridge relay adapted to be energized upon the response of the subscriber, means for deenergizing said relay upon the subscriber replacing his receiver upon the hook, and a slow acting signaling relay including normally open contacts of said cut-off relay and normally closed contacts of 70 said back-bridge relay.

Signed by me at London, England, this 75
22nd day of April, 1913.

EDWARD A. MELLINGER.
